US00D898736S

(12) **United States Design Patent** (10) Patent No.: **US D898,736 S**
Andre et al. (45) Date of Patent: **** Oct. 13, 2020**

(54) **ELECTRONIC DEVICE**

- (71) Applicant: **Apple Inc.**, Cupertino, CA (US)
- (72) Inventors: **Bartley K. Andre**, Palo Alto, CA (US); **Daniel J. Coster**, San Francisco, CA (US); **Daniele De Iuliis**, San Francisco, CA (US); **Richard P. Howarth**, San Francisco, CA (US); **Jonathan P. Ive**, San Francisco, CA (US); **Steven P.
